UNITED STATES PATENT OFFICE.

PHILIPP BALISTRERI, OF MILWAUKEE, WISCONSIN.

DESIGN FOR AN ORNAMENTAL PICTURE-FRAME.

52,233.

Specification for Design.

Patented July 30, 1918.

Application filed April 20, 1918. Serial No. 229,863. Term of patent 3½ years.

To all whom it may concern:

Be it known that I, PHILIPP BALISTRERI, a subject of the King of Italy, residing at Milwaukee, in the county of Milwaukee and State of Wisconsin, have invented a new, original, and ornamental Design for Ornamental Picture-Frames, of which the following is a specification, reference being had to the accompanying drawing, forming part hereof.

I claim:

The ornamental design for an ornamental picture frame, as shown.

PHILIPP BALISTRERI.

Witnesses:

R. S. C. CALDWELL,
H. D. CHASE.
